Primary Examiner — Cynthia Ramirez*Assistant Examiner* — Llorellys Martinez-Rivera(74) *Attorney, Agent, or Firm* — Drinker Biddle & Reath LLP(57) **CLAIM**

The ornamental design for a window component extrusion, as shown and described.

DESCRIPTION

FIG. 1 is a perspective view of a window component extrusion showing my new design.

FIG. 2 is a right side view of the window component extrusion of FIG. 1.

FIG. 3 is a left side view of the window component extrusion of FIG. 1.

FIG. 4 is a front view of the window component extrusion of FIG. 1.

FIG. 5 is a rear view of the window component extrusion of FIG. 1.

FIG. 6 is a top view of the window component extrusion of FIG. 1; and,

FIG. 7 is a bottom view of the window component extrusion of FIG. 1.

The broken lines shown in the drawings illustrate environmental subject matter only and form no part of the claimed design. A symbolic break has been shown in the drawings indicating that any portion of the window component extrusion beyond what is shown forms no part of the claimed design.
